UNITED STATES PATENT OFFICE.

FRANK F. SCOVILLE, OF SCHENECTADY, NEW YORK.

TRUCK FOR RAILROAD ROLLING STOCK.

Application filed December 18, 1924. Serial No. 756,678.

Fig. 1 is a partial plan of an engine truck embodying my invention; Fig. 2 is an end elevation thereof partly in section; Fig. 3 is a side elevation thereof; Fig. 4 is an elevation of one of the supporting rockers; Fig. 5 shows a portion of the frame having a modified form of track; Fig. 6 shows in elevation a modified form of the supporting rockers, the connecting pins being in section on line VI—VI of Fig. 7; and Fig. 7 is a bottom plan of the form shown in Fig. 6, but removed from the truck.

My invention relates to trucks for railway rolling stock and its object is to provide a centering mechanism for trucks of the "swing" or "lateral motion" type which affords any desired amount of initial resistance while permitting such lateral motion as may be required by the deflection of the truck in passing around curves. My invention also prevents undue wear and the necessity for lubrication by the provision of rolling contact between the relatively movable members in the lateral traverses of the truck. My invention is designed to provide an even distribution of the load on the rockers which support the bolster upon the truck. My invention also comprises the various features which I shall hereinafter describe and claim.

Referring to the drawings, 2 indicates the truck frame which is supported through the springs 3 on the journal boxes 4, which are mounted on the axle 5. The truck wheels 6 are secured on the axle 5. The frame 2 has parallel transversely extending trackways 7, each of which has teeth 8 with bevelled upper faces arranged at intervals along one side of each such track 7. Operating along the trackways 7 are the rockers 9, which are pivotally mounted upon and support the bolster 10. The rockers 9 have lugs 11 along their outer side faces which engage the teeth 8 in the trackways 7 to prevent the rockers from slipping out of place in such trackways 7. The faces 12 of the rockers are arc-shaped, but each has a central flattened portion 13 which furnishes an initial resistance to movement of the frame 2 relative to the bolster 10 and also assists in bringing the bolster to centered position after lateral movement.

In Figs. 1, 3 and 4 I have shown the bolster displaced laterally to an extreme extent from the vertical axis of the truck, which is indicated in Fig. 3 by the line A, while the

vertical axis of the bolster in such displaced position is indicated by the line B. It will be seen that, as shown in Figs. 3 and 4, the contact point of the rockers on the track is continuously in advance of the bearing pins 14, which produces a more even distribution of the load on the rockers 9 and thereby overcomes any tendency of the bolster to override the outer rocker.

To prevent the bolster from becoming disengaged from the truck frame in case of derailment or other emergency chains or other limiting means may be employed.

In Fig. 5 I have shown a modified form 70 of trackway in which the track on the truck frame 15 is formed partly in shallow arcs 16, and thereby tends both to limit definitely the travel of the rockers therealong and to center them.

In Figs. 6 and 7 I have shown a modified form of supporting rocker for the bolster in which the rocker 17 instead of having a flattened central portion in its arc-shaped face 18 has a kidney-shaped opening 19 for 80 two pins or fulcrum bearings 20, 21, each half of the opening being of slightly greater width than the pin contained therein so as to permit the rocker 17 to move about the pins without binding. The rockers 17 are 85 arranged in the same horizontal plane so that when the bolster 22 is in centered position both pins 20, 21 will take up the same proportion of the weight of the bolster and there will thus be a certain amount of initial 90 resistance to overcome before a rocker 17 can tilt and thus shift the weight to one or the other of the pins.

It will be seen that as the rockers roll laterally away from the centered positions, 95 the distance between their points of support and the trackways in which they operate increases with the result that there is a constant tendency for the rockers to return by gravity to centered position.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In a railroad truck, the combination of a frame; trackways extending trans-

versely of the frame; a bolster adapted to move transversely relative to the frame; rockers supporting the bolster having arc-shaped faces engaging said trackways, each 5 of said rockers having a portion of the face contacting with the trackway of a contour departing from the arc in which the remainder of said face is struck to provide an initial resistance to motion of the bolster 10 relative to the truck.

2. In a railroad truck, the combination of

a frame; a bolster adapted to move laterally relative thereto; supports for the bolster journaled in the bolster and having a face 15 engaging the frame with a rolling contact, the point of attachment to the bolster being so disposed with reference to the said face as to offer a variable resistance to progressive lateral movement of the bolster relative to the truck.

FRANK F. SCOVILLE.
